UNITED STATES PATENT OFFICE

GEORGE S. CHILES, OF ST. LOUIS, MISSOURI, ASSIGNOR TO SCULLIN STEEL COMPANY,
OF ST. LOUIS, MISSOURI, A CORPORATION OF DELAWARE

GRAB IRON OR LADDER RUNG

Application filed March 5, 1929. Serial No. 344,472.

This invention relates to grab irons and ladders of the kind that are used on freight cars.

The main object of my invention is to provide a grab iron or ladder rung for freight cars that is exceptionally strong and rigid, light in weight and inexpensive to manufacture.

Another object is to provide a sheet metal grab iron or ladder rung of the character above described, that has integral portions for attaching it to a supporting structure.

Figure 1 is a fragmentary elevational view of a freight car body equipped with grab irons or ladder rungs constructed in accordance with my invention.

Figure 2 is a top plan view of one of said grab irons.

Figure 3 is a side elevational view of said grab iron, looking at the inner side of same; and

Figure 4 is an end elevational view of said grab iron.

In the accompanying drawings which illustrate the preferred form of my invention, A designates one wall of a freight car body and B designates grab irons or ladder rungs that are attached to said wall. Said grab irons or ladder rungs are formed from sheet metal and each one of said members comprises a substantially tubular, bar-like portion 1 provided at its opposite ends with integral devices that perform the dual function of spacing devices and attaching devices. In the preferred form of my invention, as herein illustrated, the combined spacing and attaching devices just referred to consist of substantially L-shaped members whose legs 2 are disposed at substantially right angles to the tubular, bar-like portion 1 and whose legs 3 are disposed in substantially parallel relationship to said tubular, bar-like portion 1. The legs 3 are adapted to bear against the wall A of the car body and are provided with

holes 3^a for receiving fastening devices 3^b that penetrate into or project through the wall of the car body.

At the ends of the bar-like portion 1 of my improved grab iron or ladder rung are inclined end walls 4 that form in effect closures

for the ends of said tubular portion 1, said end walls 4 merging into the angularly-disposed flanges or legs 2 which hold the tubular, bar-like portion 1 of the grab iron or ladder rung in spaced relation with the wall A of the car body. If desired, the combined attaching and spacing devices, formed by the parts 2 and 3, may be provided with pressed ribs 5 that reinforce and strengthen the same, the ribs 5 on the spacing flanges 2 preferably merging into similar reinforcing pressed ribs 5^a on the end walls of the tubular, bar-like portion 1.

A grab iron or ladder rung of the design above described can be constructed easily and at a low cost from a flat plate or strip of metal by a die-shaping or pressing operation. It is of less weight and of less cross-sectional area than a grab iron or ladder rung formed from a solid bar, but nevertheless, it is stronger and more rigid than the conventional solid grab irons and ladder rungs now used on freight cars. While I have herein illustrated my invention, embodied in a grab iron or ladder rung that is provided with integral portions which are used to hold it in spaced relation and also to connect it directly to the car body on which it is used, I wish it to be understood that it is immaterial, so far as my broad idea is concerned, what means or method is used to attach said grab iron or ladder rung to the supporting structure which carries it.

Having thus described my invention, what I claim as new and desire to secure by Letters Patent is:

1. A grab iron or ladder rung for freight cars, consisting of a pressed metal member having a substantially tubular, bar-like portion whose ends are closed by inclined end walls that merge into spacing devices which are disposed at substantially right angles to said bar-like portion, and laterally-projecting flanges on said spacing devices.

2. A grab iron or ladder rung for freight cars formed from a flat plate or strip of metal that is pressed or die-shaped so as to produce a bar-like member of substantially tubular shape in cross section provided with oppo

sitely-inclined end walls, substantially L-shaped devices integrally connected with said end walls for attaching the rung to the car and holding the bar-like member of same spaced away from the car, and pressed reinforcing ribs in said end walls and L-shaped devices.

GEORGE S. CHILES.
